AUTOMOBILE

Harley J. Earl, Grosse Pointe Farms, Mich., assignor to General Motors Corporation, Detroit, Mich., a corporation of Delaware

Application December 28, 1956, Serial No. 44,351

Term of patent 7 years

(Cl. D14—3)

Figure 1 is a side elevational view of an automobile, according to my new design with the other side thereof being the same;

The dominant features of my design reside in the full line portions of the drawings.

I claim:

The ornamental design for an automobile, substantially as shown and described.
